Related U.S. Application Data

CLAIM

(63) Continuation of application No. 29/501,803, filed on Sep. 9, 2014, now Pat. No. Des. 762,223.

The ornamental design for a display screen or portion thereof with animated graphical user interface, as shown and described.

(51) **LOC (11) Cl.** **14-04**
(52) **U.S. Cl.** **USPC** **D14/488**

DESCRIPTION

(58) **Field of Classification Search**

FIG. 1 is a front view of a display screen or portion thereof with animated graphical user interface showing a first image of the claimed design;

USPC ..... D14/485—495
CPC .. G06F 3/0481; G06F 17/24; G06F 17/30056;
G06F 3/04845; G06F 2203/04803–2203/04805; H04N 1/00198;
H04N 21/234336; G06T 13/80

FIG. 2 is a second image thereof;

See application file for complete search history.

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

(56) **References Cited**

The appearance of the animated image sequentially transitions between the images shown in FIGS. 1-7. The process or period in which one image transitions to another forms no part of the claimed design.
